UNITED STATES PATENT OFFICE.

WILLIAM HARRISON CORBETT, OF PORTLAND, OREGON.

FRICITION-CLUTCH.

No. 841,230.

Specification of Letters Patent.

Patented Jan. 15, 1907.

Application filed March 8, 1906. Serial No. 304,817.

To all whom it may concern:

Be it known that I, WILLIAM HARRISON CORBETT, a citizen of the United States, residing at Portland, in the county of Multnomah and 5 State of Oregon, have invented new and useful Improvements in Friction-Clutches, of which the following is a specification.

This invention relates to friction-clutches; and it consists in certain improvements in 10 the construction thereof, as will be herein-after fully described, and pointed out in the claims.

The invention is illustrated in the accompanying drawing, wherein A marks the driving-shaft. The driving member B is mounted 15 on this shaft. It comprises the hub b, from which extends the annular web b'. The outer end of the web forms a complete annulus b³. The friction-ring B' has the cone friction-surface b⁴, this surface being 20 interiorly faced. It is secured to the annulus b³ by the bolts b⁵.

The driving member is keyed to the shaft by any convenient means, one of the keys b² 25 being shown. The driven member C has the cone friction-surface c, which is arranged to act in conjunction with the friction-surface b⁴. An extended hub C' is formed in connection with the driven member, and this has 30 mounted on it the pulley D, a part being shown in dotted lines in the drawing.

Arranged between the hub B and the driven member C is the thrust-ring E. It has the arm e, extending through the aperture b⁶ in the web b'. Adjusting-screws e' are screwed into the ends of these arms, and the lock-nut e² is provided for securing them in adjustment. Thrust-levers F, which are 35 in the form of bell-cranks, are pivoted on the hub b by means of the pins f. One arm f' of the bell-crank lever is engaged by the cam-surface g on the sliding block G, the action of the cam-surface being to spread the arms f' and to move inwardly the arms f² against the 40 thrust-screws e', and these, acting through the arms e and ring E, move the driven member into engagement.

It will be noted that the driving member of this clutch normally rotates and that the annulus b³ forms a complete closure at the larger end of the cone-surface b⁴, thus forming an oil-cavity in which oil may be placed and retained through the action of centrifugal force.

5 This construction of clutch also permits of the weighting of the lever F, so that it nor-

mally swings back, so as to free the clutch without the interposition of springs or like mechanisms. In the construction shown I have provided the weights f³ on the arm f² 60 for accomplishing this purpose. The sliding block G has the groove g', in which is arranged the ring H. The ring H has the usual pins h, which are engaged by the operating-lever.

Under some conditions the driven member 65 may be made the driving member and the driving member the driven member.

What I claim as new is—

1. In a friction-clutch, the combination of 70 the driving member having the cone friction-surface interiorly faced; the driven member having the friction-surface adapted to engage said friction-surface; the thrust-ring E adapted to operate upon the driven member 75 having the arm e extending through the driving member; thrust-levers F mounted on the driving member and adapted to operate against the arm e for throwing the members 80 into engagement.

2. In a friction-clutch, the combination of 85 the driving member comprising a hub b, the web b' having a complete annulus b³ at its outer edge and the friction-ring B' secured thereto, its larger end next to the annulus; the driven member C having a friction-surface for engaging the friction-surface on the friction-ring; the thrust-ring E having the arms e extending through the web b'; adjusting-screws on said arms; the bell-crank levers 90 F pivoted on the hubs b one arm of the bell-cranks operating upon the thrust-screws; and means for operating the opposite end of the bell-crank to throw the clutch into engagement.

3. In a friction-clutch, the combination of 95 the driving member comprising a hub b, the web b' having a complete annulus b³ at its outer edge and the friction-ring B' secured thereto, its larger end next to the annulus; the driven member C having a friction-surface for engaging the friction-surface on the friction-ring; the thrust-ring E having the arms e extending through the web b'; adjusting-screws on said arms; the bell-cranks operating upon the thrust-screws; and means for operating the opposite ends of the bell-cranks to throw the clutch into engagement, said bell-cranks being weighted to move out of engagement with the thrust device under 100 the action of centrifugal force.

4. In a friction-clutch, the combination of

a driving member and driven member, one of which is movable axially; thrust mechanism arranged at the opposite end of the clutch from the moving member; and a connecting mechanism communicating the thrust action from the thrust devices to the moving member, said connecting mechanism extending through the relatively stationary member.

5. In a friction-clutch, the combination of the driving and driven members having friction-surfaces adapted to be brought into engagement; levers for forcing said members into engagement; said levers being mounted

on a normally rotating part and being so weighted as to throw them out of engagement to release the clutch under the action of centrifugal force; and devices operating upon said levers for setting and releasing the clutch.

In testimony whereof I have hereunto set my hand in the presence of two subscribing witnesses.

WILLIAM HARRISON CORBETT.
